DUMP CAR

Alfred K. Pehrson, Bellevue, Pa., assignor, by
mesne assignments, to Koppel Industrial Car
and Equipment Company, McKees Rocks, Pa.,
a corporation of Pennsylvania

Application January 6, 1932, Serial No. 584,986

8 Claims. (Cl. 105—271)

My invention pertains to dump car body tilting mechanisms and particularly those mechanisms which include a fluid pressure actuated piston.

5 In the dump cars as now used on the railways and particularly the cars of larger capacity the car body in dumping pivots about trunnions mounted at the sides of the car. Under these conditions the maximum body tilting effort is
10 required at the beginning of the dumping movement and the minimum of effort is required near the end of the dumping movement. The reasons for this will be apparent upon considering that when the car body is horizontal and in load carrying position the center of gravity of the load and car body are farthest from the trunnions and as the body is tilted this moves nearer to the trunnions. Also the shifting of the load contained in the body assists in the tilting of the
15 body both by reason of resting upon the side doors beyond the trunnions and because of becoming less as the tilting continues.

The use of the larger types of car body has introduced a troublesome condition as regards
25 the dumping mechanism. Fluid pressure actuated mechanism comprising a reciprocating piston contained within a cylinder mounted upon the underframe of the car are used on railway dump cars and the necessary length of piston to secure an efficient dumping angle results in the
30 need of large cylinders to contain such pistons. The excessive size of cylinders necessitates high mounting of the bodies and the long pistons are liable to be distorted. To overcome these conditions various methods have been used among
35 which is the method of employing telescoping cylinders. In all of these methods, however, the mechanisms while using their full power to start the dumping of the body do not need such power
40 to complete the dumping movement.

An object of the present invention is to take advantage of the decreasing amount of power necessary as the dumping proceeds and to interpose a suitable mechanism between the piston
45 and car body whereby the car body is moved relative to the piston after the initial dumping movements thereby reducing the length of piston and stroke.

One method of accomplishing such object is
50 disclosed in the following specification and appended drawings but it will be understood that the particular means employed are only illustrative and various equivalent means and modifications thereof will be apparent to those skilled in
55 the art. In the drawings the car body is shown

resting upon the underframe and adapted to roll thereon until the trunnions engage and thereafter pivot thereon. This is a refinement of the invention as applied to cars supported upon the trunnions and adapted to pivot upon such supports, but it will be apparent that the method disclosed in the drawings will be equally adaptable to either type. 5

No particular form of car body is disclosed as it will be understood that the invention can be used with any type of body of sufficient strength whether of the drop door type or lift door type. Likewise, the underframe and power dumping mechanism can be of any type or form adaptable to the particular car desired. Should the car 15 body be applied to a road vehicle and another type of power mechanism other than fluid pressure means be employed the invention can obviously be used.

In the drawings Fig. 1 is a transverse section of 20 a car embodying the invention with the car body in load carrying position. Fig. 2 is a transverse section of the car with the body in fully tilted position. Fig. 3 is a fragmentary view of the side elevation of a car showing the invention. Fig. 4 25 is a plan view of Fig. 3.

Referring in detail to the drawings, reference character 1 indicates a dump car having a car body 2 supported upon an underframe 3 having the usual trucks 4. Spaced in pairs longitudinally 30 of the underframe 3 are suitable members 5 to which are secured bearings 6 between which are mounted the cylinders 11 of the fluid pressure actuated mechanism. Suitable trunnions 7 are secured adjacent the sides of the car body and 35 adapted to be supported in bearings 8 secured to the underframe. The car body pivots about these trunnions on the bearings 8 during the major portion of the dumping movement.

Interposed between the cylinder 11 and car body 40 are the mechanisms for effecting the tilting of the car body and movement thereof relative to the cylinder piston during the dumping movement. These mechanisms are mounted upon a yoke 9 secured to a reciprocating piston 10 mounted within the cylinder 11 and comprise a bell crank 12 pivotally mounted on each end of the yoke with one arm thereof pivoted to the underframe at 16 and the other arm pivoted at 17 to a member 13 secured to the body 2 by means of 45 a bracket 14. Duplicate mechanisms are mounted on opposite sides of the car body when it is desired to have the body tiltable to either side of the underframe. 50

It will be observed that in Fig. 1 where the car 55

body is shown in horizontal or load carrying position the bearing 15 of the bracket 14, by means of which the member 13 is connected to the car body, is a material distance below the upper limits of the cylinder and piston. The spacing of this bearing in the bracket 14 can obviously be varied to suit the particular conditions under which the car is to operate. The member 13 is shown in the drawings with a curved end portion. 10 This member may or may not have this curved end portion depending on the conditions under which the mechanism is applied to the car. In this particular instance the curved portion serves the purpose of providing a clearance between the member 13 and cylinder when in the lower tilting position.

During the tilting of the body the action of the mechanism is as follows: the upward stroke of the piston and consequently yoke 9 causes rotation 20 of the attached bell cranks 12 upon their connections 16 to the underframe which in turn causes the ends 17 of the bell cranks to move transversely of the yoke and inwardly of the underframe of the car. This upward and inward movement of the ends 17 of the bell cranks causes corresponding upward and inward movements of the members 13 secured thereto. The resultant movement of the members 13 effecting a vertical movement of the brackets 14 and consequently of 25 the car body.

Referring to Figs. 1 and 2 of the drawings in which the car body is shown in horizontal and fully tilted positions respectively, it will be noted that in Fig. 1 the connection between the bracket 35 14 and member 13 is below the connection between the bell crank 12 and yoke 9. In Fig. 2 the positions are reversed indicating that during the upward stroke of the piston and consequently the arm of the bell crank secured to the yoke 9, 40 the bracket 14 has moved a greater vertical distance than the piston so that there has been obtained an increased vertical movement of the body with relation to the piston than would have been possible had the piston been fixed to the car body. 45 The car body, during the tilting movements has pivoted about the trunnions on the side of the underframe opposite to the mechanism and the bell crank has pivoted about a point intermediate the sides of the underframe. This difference in 50 the path of movements of the two pivoting parts is compensated for by the pivoting of the member 13 on the connections to the bracket 14 and bell crank 12. In this manner the member 13 remains as a tension member throughout the 55 movement of the car body. Thus, the combined upward and inward movement of the end 17 of the bell crank has resulted in an increased vertical travel of the end of the body adjacent the piston than would have been possible had the piston 60 been fixed to the car body.

In cars of the type now mostly in use the discharge of the lading at the sides of the car is effected by having the sides of the car comprised of doors pivotally mounted adjacent the floor of 65 the body and acting as aprons to discharge the lading away from the car and by reason of their construction the shifting of the load onto these doors assists in the tilting of the car body. The conditions resulting therefrom may be such that 70 the load on the door would tend to tilt the car body beyond the position shown in Fig. 2, which would cause the body to leave the underframe. To prevent this, a member 18 is provided which in the preferred form is a section of chain secured 75 to the end of the lever 13 and to the car body to

prevent movement of the car body beyond the position shown in Fig. 2 of the drawings.

At the descending side of the body the piston in the cylinder on that side of the car must have a limited downward movement in order that the 5 various parts of the mechanism can adjust themselves to the position shown in Fig. 2. By referring to Fig. 3 of the drawings it will be noted that a sufficient clearance for this movement has been provided between the underside of the 10 yoke 9 and cylinder 11.

Referring now to Fig. 1 of the drawings where the car body is horizontal and considering power to be applied to the cylinder 11, the upward thrust of the cylinder 9 is applied to the car body 15 through the member 13. Drawing the line "A" through the ends of the member 13, the turning moment applied to the body is the product of the force acting along the line "A" and the perpendicular distance from line "A" to the pivot point 20 of the car body on the opposite side of the underframe. The capacity of the car body being known the size of cylinder to produce a sufficient turning moment to tilt the car body can thus be computed. 25

As previously explained the effort required to tilt the car body becomes less after tilting begins and referring to Fig. 2 of the drawings, it will be seen that the turning moment there applied to the body is considerably less due to the decreased 30 distance between the line "A" and the pivoting point of the body.

The cause of this reduction in the perpendicular distance of the line "A" from the pivoting point of the car body has been the changing 35 of the position of the member 13 with relation to the car body. The resultant of such change has been a movement of the car body with relation to the cylinder piston so that for the same length of stroke of the piston the car body has 40 moved a greater vertical distance or through a greater tilting angle than would have been possible had the piston been fixed to the car body.

From the above it will be apparent that in this manner by properly proportioning the various parts of the mechanism any desired movement can be obtained while retaining all the advantages of increased stability and strength resulting from a short piston travel and low 45 height of car. 50

Having thus described the invention, what I claim as new and desire to secure by Letters Patent is:

1. In a dump vehicle in combination, an underframe, a body tiltable about each side of the 55 underframe on trunnions, a power source adjacent each side of the underframe, a lever mounted on the moving portion of each power source and fulcrumed on the underframe inwardly of said mounting, a depending bracket adjacent 60 each side of the body and having its lower extremities depending below the connection of the lever to the power source when the body is in horizontal position, and a member connected to the lower extremity of the bracket and to the 65 free end of the lever.

2. In a dump vehicle in combination, an underframe, a body tiltable about one side thereof, a power source, including a movable portion, adjacent the opposite side of the underframe, a lever 70 pivoted intermediate its ends upon said movable portion of the power source, a fulcrum for said lever upon the underframe, a member pivotally mounted upon the free end of said lever, a bracket depending from the body, one end of the mem- 75

ber being pivoted to the bracket in a position below its connection to the lever when the body is in horizontal position.

3. In a dump vehicle in combination, an underframe, a body tiltably mounted thereon, power actuated body tilting means adjacent a side of the underframe, a bell crank pivoted to the tilting means, a connection between one end of the bell crank and the underframe, a depending rigid member on the body, an arm having one end pivoted to said depending member, a link connection between the opposite end of the arm and the body, and a pivotal connection between the bell crank and arm intermediate the ends of the arm.

4. In a power actuated dump vehicle, in combination, an underframe, a body tiltably mounted on the underframe, a power source including a piston, a bell crank pivotally connected to the piston and underframe and having a portion projecting outwardly of the connection to the piston, an arm pivotally mounted intermediate its ends on said outwardly projecting portion of the bell crank, a bracket depending from said body, a pivotal connection between one end of said arm and the bracket, and a member pivotally connected to the other end of said arm and to said body.

5. In a power actuated dump vehicle, in combination, an underframe, a body tiltably mounted thereon, a power source mounted on the underframe adjacent one side thereof beneath the body and including a piston, a bell crank pivoted intermediate its ends on the piston, a pivotal connection between the inner end of the bell crank and the underframe, a lever pivotally mounted intermediate its ends on the outer end of the bell crank, and vertically spaced operative connections between the ends of said lever and the body.

40 6. In a power actuated dump vehicle, in combination, an underframe, a body tilting about one side of the underframe, a power source

mounted adjacent one side of the underframe, a piston in said power source movable towards the body, a yoke on said piston, a bell crank pivoted to each side of the yoke, a connection between one end of each bell crank and the underframe, spaced brackets depending from the body, an arm pivoted intermediate its ends to the free ends of each bell crank, a connection between one end of each arm and the adjacent bracket, a link connection between the other end of each arm and the body.

7. In a power actuated dump vehicle, in combination, an underframe, a body, means on the body and underframe providing selective tilting of the body to either side of the underframe, a power source adjacent each side of the underframe, a movable piston in each power source, a yoke mounted on each piston, a bell crank pivoted on each side of each yoke, connections between one end of each bell crank and the underframe, brackets depending from the body adjacent each side thereof, an arm pivotally mounted on each bell crank, and a connection between one end of each arm and the adjacent bracket below the connection between said arm and bell crank.

8. In a dump vehicle, in combination, an underframe, a body mounted on the underframe for tilting about one side thereof, a power actuated body tilting mechanism mounted adjacent the opposite side of the underframe, an upwardly moving piston in said mechanism, a bell crank pivotally connected with said piston, a pivotal connection between one arm of the bell crank and the underframe inwardly of the piston, the other arm of the bell crank projecting outwardly of said underframe connection, a bracket depending from the body and below said other arm of the bell crank, and a member pivotally connected to said other arm of the bell crank and to said depending bracket below said connection to the bell crank.

ALFRED K. PEHRSON.
